Inventor,

Lorenzo D. Benner,

per A. B. Upham,
Atty. in fact:

UNITED STATES PATENT OFFICE.

LORENZO D. BENNER, OF PEORIA, ILLINOIS.

CHECK-ROWER.

SPECIFICATION forming part of Letters Patent No. 312,179, dated February 10, 1885.

Application filed March 14, 1884. (No model.)

To all whom it may concern:

Be it known that I, LORENZO D. BENNER, of Peoria, in the county of Peoria, in the State of Illinois, have invented an Improved Check-Rower; and I do hereby declare that the following is a full, clear, and exact description thereof, reference being had to the annexed drawings, making a part of this specification, in which like letters of reference refer to like parts, and in which—

Figure 1 represents a plan view of the device; Fig. 2, a vertical longitudinal section through the center; and Fig. 3, a detail.

This invention is in that line of check-rowers for corn-planters in which a knotted wire or cord intermittently reciprocates a bifurcated lever whose movement operates, through intermediate mechanism, the feed-slide of the planter, and relates to the construction of an improved device for converting the movements of the bifurcated lever into a positive, self-locking, intermittent reciprocation of the feed-slide.

My invention for this purpose consists, essentially, of two laterally-contiguous oppositely longitudinally reciprocating bars, having at one end of each a bent channel, in which the hooked end of a rod, connected with the bifurcated lever, can slide from the channel of one bar to the channel of its neighbor when said rod is pushed in one direction, but, when it is pulled in the opposite direction, engages with the notched bottom of said channel and moves the bar back with it, at a forward movement passing from one bar to the other, and at the return-stroke bringing the bar back with it. Since there is a bifurcated lever at each side of the planter, there are of course two hooked rods and channels at each end of each bar.

In the drawings, R is a portion of the transverse beam, at the ends of which are arranged the bifurcated levers, (not shown,) and at the center of which is my device.

ss are the hooked rods before mentioned, whose ends (not shown) are pivoted to the bifurcated levers, by which they are given, through the agency of the knotted wire and a retracting-spring, a reciprocating movement.

The bars A are formed at each end with a groove of the shape shown, of varying depth,

whose ends open out through the contiguous sides of the bars, as shown in the drawings. At the bend of each of these channels a, I usually have a vertical hole, a', through the bar 55 thereat, from the side of which, toward the end of the bar, the bottom of the channel a slopes downward and outward, while at the opposite side of said hole the bottom of the channel is depressed and slants upwardly 60 and outwardly therefrom. These channels or grooves a are so conformed that one end of one opens into one end of its neighbor whenever the bars A are at their opposite points of reciprocation. By this means the 65 hooked end of the rod s can slide from the hole a' of one channel up its inclined bottom and the inclined bottom of the contiguous channel until it drops into the hole a' of the latter. When, however, the said hooked 7c end is drawn in the opposite direction, it engages with the elevated side of the hole a' in which it is and pulls the bar A along with it. I sometimes remove the delta-shaped projection that lies between each channel a and the 75 contiguous faces of the bars A, for, practically, there is no necessity in having the same; and not only this, but should the two bars A make, by any means, only half a stroke, the two projections would form an obstruction upon which 80 the hook of the rod s might catch, and the machine be thereby injured.

To give the bars A a reciprocating movement in opposite directions when one only is reciprocated, they are connected to the centrally-pivoted lever D by a pin projecting from each into the slots d of said lever. At one end of this lever is formed a segment of a gear, D', the center of which lies in the pivotal pin E. Meshing with this segmental gear D' is 90 the mutilated pinion, G, from a crank-pin of which runs the connecting-rod H to the feed-slide of the planter or to a lever intermediate thereto. (Not shown.) The diameter of this pinion G is so proportioned relative to the segmental gear D' that the comparatively short oscillation of the latter shall communicate to the former an exact semicircular reciprocation. Since the teeth at one side alone of the pinion G mesh with the gear D' in both its 95 semi-revolutions, the teeth at its other side are superfluous, and I therefore form said pinion 100

mutilated, as described. This pinion G is pivotally secured upon the laterally-projecting arm Q, cast as a part of the plate P. Upon said plate rest the bars A, which are kept in 5 place thereon by means of the upwardly-projecting rims P'.

On the under side of the bars A are feet B, which fit in between said rims or flanges P' and take all the wear ensuing from the reciprocation of said bars. The plate P is bolted to the upper side of the transverse beam R, and about both it and the bars A extend the straps c, by which the latter are prevented from being displaced by any shock that would 15 tend to throw the same from the plate P. The heads of the bolts by which the plate P is secured to the beam R are beneath the arched portions of the bars A, and therefore do not interfere therewith. This arched portion is 20 made just high enough to give easy room between the same and the plate P for the lever D.

The lever D, when performing its work of oppositely reciprocating the bars A when one is moved, tends to press together the contiguous 25 sides of said bars, and thus cause some little friction. To stop this loss of power by friction I extend the pivotal pin E of the lever D and give it a friction-roller, e, by which the two bars are kept slightly apart and the 30 desired end accomplished. It is necessary to recess somewhat the bars A to make room for said roller.

To keep the hooked ends of the rods s from getting out of the channels a, I provide each 35 rod with a horizontally-elongated eye, T. Each of these eyes T terminate in a screw-threaded shank which passes through the beam R, and is vertically adjustable therein by nuts above and below, as in Fig. 2. These eyes are 40 elongated to permit the rods s passing therethrough to change their hooked ends from one hole a' to another.

There are other ways of communicating the motion of the reciprocating bars A to the feed-slide besides the means previously described. 45 The connecting-rod H might be attached directly to the lever D, and the gearing dispensed with, but the locking device would be somewhat difficult to arrange in a perfect working 50 condition.

What I claim as my invention, and for which I desire Letters Patent, is as follows, to wit:

1. In a check-rower, the combination, with a hooked rod or equivalent device adapted 55 to receive an intermittent reciprocating motion, of two bars, and means whereby the longitudinal reciprocation of one shall oppositely affect the other, and adapted to cause the said hooked rod to engage with first one and then 60 with the other of the bars, for the purpose set forth.

2. The combination of two bars, means whereby the longitudinal reciprocation of one bar shall oppositely affect the other, and each 65 having a groove whereby a hooked rod in either of said grooves shall, when pulled, en-

gage therewith, but when oppositely moved shall slide from the groove in which it was to the groove of the other bar, substantially as and for the purpose specified.

3. Two bars provided with the bent grooves or channels a, having uneven or notched bottoms, as described, in combination with means, substantially as described, whereby the longitudinal reciprocation of one of said bars shall 75 oppositely move the other, as and for the purpose specified.

4. In a check-rower, two bars having the bent grooves or channels a, the bottoms of which are uneven, as described, in combination 80 with a centrally-pivoted lever pivotally connected with each of said bars, substantially as set forth.

5. In a check-rower, two bars having the bent grooves or channels a, in combination 85 with a centrally-pivoted lever pivotally connected with each of said bars, and having means, substantially as described, whereby its oscillations may be transmitted to the feed-slide of the planter.

6. Two bars having the bent grooves or channels a, in combination with a centrally-pivoted lever pivotally connected with each of said bars; and having at one end thereof a segment of a gear meshing with a pinion, to 95 which it imparts a reciprocatory semi-revolution, for the purpose set forth.

7. Two bars having the bent grooves or channels a therein, in combination with the centrally-pivoted lever, D, having slots d and 100 segmental gear D', pins projecting into said slots from the said bars, the mutilated pinion G, and rod connected therewith, substantially as and for the purpose specified.

8. In a check-rower, two bars having the 105 bent grooves or channels a, in combination with means, substantially as described, whereby the said bars are oppositely reciprocated and their motion transmitted in semi-revolutions to a pinion, from which the feed-slide of the 110 planter is operated.

9. In a check-rower, two bars having grooves or channels a and the hooked rods s, in combination with the plate P, having pivotal pin E and friction-roller e, the lever D, pivoted 115 about said pin E and pivotally connected with the said bars, and means, substantially as described, for conveying the oscillatory movement of said lever to the feed-slide of the planter.

10. In a check-rower, the bars A, having grooves a and the hooked rods s in combination with the plate P, having elevated rims P' and the pin E, the lever D, pivoted to said plate, pivotally connected to the said bars A, 125 and means, substantially as described, whereby its oscillation is transmitted to the feed-slide of the planter.

11. In a check-rower, the bars A, having grooves a, feet B, and centrally arched, as 130 shown, in combination with the plate P, having rims P', the lever D, having slots d, fric-

tion-roller *e*, and pins projecting from said bars into said slots.

12. In a check-rower, the plate *P*, having rims *P'* and a pivotal pin, *E*, near the center 5 thereof, in combination with two bars having feet *B*, adapted to slide between said rims *P'*, and means, substantially as described, whereby said bars may be oppositely reciprocated, for the purpose set forth.

13. The combination, with the bars *A*, having grooves *a*, and means, substantially as described, whereby the reciprocation of one of said bars shall be oppositely communicated to its neighbor, the transverse beam *R*, hooked 15 rods *s*, and the horizontally-elongated vertically-adjustable eyes *T*, for the purpose specified.

14. The transverse beam *R* of a corn-planter, the plate *P*, secured thereon, and the mutilated 20 pinion *G*, having means of communication

with the feed-slide of the planter, in combination with the lever *D*, centrally pivoted to said plate *P*, and having a segmental gear, *D'*, formed at one end thereof, the bars *A*, pivotally connected with said lever, bent grooves 25 or channels *a*, formed, as described, at the extremities of said bars, the rods *s*, hooked at one end of each and pivotally secured at their other ends to the bifurcated levers of the planter, the eyes *T* for retaining said rods in place, 30 and means for retaining said bars *A* upon the plate *P*, substantially as and for the purpose specified.

In testimony that I claim the foregoing invention I have hereunto set my hand this 8th 35 day of March, 1884.

LORENZO D. BENNER.
